CLAIM

The ornamental design for a “brochure stand”, as shown and described.

DESCRIPTION

FIG. 1 is a front elevational view of a BROCHURE STAND showing my new design;

FIG. 2 is a rear elevational view of the design illustrated by FIG. 1;

FIG. 3 is a top plan view of the design illustrated by FIGS. 1 and 2;

FIG. 4 is a perspective view of the design illustrated by FIGS. 1 and 2;

FIG. 5 is a front elevational view of a BROCHURE STAND having two central supporting elements in stacked relationship, including a plurality of trays extending therefrom, mounted to a supporting stand;

FIG. 6 is a rear elevational view of the design illustrated by FIG. 3; and,

FIG. 7 illustrates the design of FIGS. 3–4 in which the two central supporting elements are rotated out of alignment relative to each other.
